UNITED STATES PATENT OFFICE.

JAMES FENTRESS, OF CHICAGO, ILLINOIS.

GASOLENE-PROOF HOSE.

1,255,867.

Specification of Letters Patent. Patented Feb. 12, 1918.

Application filed February 20, 1915, Serial No. 9,536. Renewed December 26, 1917. Serial No. 208,981.

To all whom it may concern:

Be it known that I, JAMES FENTRESS, a citizen of the United States, residing at Chicago, in the county of Cook and State of Illinois, have invented a certain new and useful Improvement in Gasolene-Proof Hose, of which the following is a specification.

This invention is a tubing capable of controlling and permitting the flow of gasoline without the escape through the walls of the tubing, either in the form of vapor or otherwise, of any portion of the gasoline. So far as I have been able to learn, by an extended professional experience involving many experiments, the device of this invention is the first tubing to successfully and properly handle gasoline.

As is well known, gasoline is highly inflammable and even a small quantity of its vapor in a room renders the danger of fire in that room very great. Previous devices have permitted gasoline vapor to work through the wall of the tube and permeate the room with possible disastrous results. The object sought to be accomplished and accomplished by this invention is to do away with all possibility of any happening of this kind. A further object is to provide a tubing which is so little affected by the gasoline passed through it that it remains one hundred per cent. efficient for an indefinite time.

The invention consists in a device which carries out all of the above objects, which can be easily and cheaply made and satisfactorily handled. It also consists in the features and details hereafter set forth.

In the drawings, which show the most satisfactory form of tubing embodying this invention:

Figure 1 is a side view of the tubing, the different layers being broken away in order to clearly show the construction.

Fig. 2 is a cross-sectional view of Fig. 1.

As in all modern tubing, a metallic supporting frame 11 is provided, preferably of steel because it is cheapest. Over this steel frame 11 is placed a paper covering 12 which is in turn covered by a cloth braid 13. Layers 12 and 13, just referred to, serve the function of supporting a layer of gelatin 14 and separating it from the metal tube 11. In the prior art, attempts have been made to apply a coating of gelatin material directly to the metal frame 11 but with disastrous

results because there is a chemical action between the iron or steel of the tube 11 and the gelatin 14 which, in a very short time, destroys the gelatin (gelatin being the best known gasoline resisting flexible material). Over coating of gelatin composition 14 is placed another layer of cloth braid 15 and a second layer of gelatin composition 16. In very light tubing layers 15 and 16 might be omitted but it is preferable to have them. Two layers of gelatin reinforced by the intervening of cloth braid 15 work much better than an attempt to provide an extra thick layer of gelatin without the intervening reinforcing layer of cloth braid 15. Over the gelatin layer 16 is placed another layer of relatively thin cloth braid 17 and the whole is covered by a thick water-proof woven cotton jacket 18. This cotton jacket is not rubber coated for the reason that gelatin deteriorates so that it is not gasoline-proof when heated to the 125 degrees, or upward, required for the proper vulcanization of rubber. Owing to the entire absence of rubber in the device and the fact that gelatin is soluble in water, though insoluble in gasoline, this tubing cannot be used as a water-carrying hose, for the water works through between the coils of the metal support 11 and coverings 12 and 13 to attack the gelatin layer 14, but the device is a perfect gasoline carrier coming up to all the specifications heretofore set forth which can possibly be required of it.

The outer braided covering 18 is made of such heavy closely woven treated thread so that it is for all practical purposes water-proof and, therefore, keeps the water which may accidentally come in contact with the outside of the hose from permeating the hose and thus attacking the layers of gelatin. It is also made sufficiently strong and stiff to protect the hose from either sharp blows accidentally applied to its outside or from injury due to some one stepping on the hose.

The gelatin composition used in this device may be made of any satisfactory composition which acts as a proper gasoline resistant, one common form well known in the art being a mixture of glue, glycerin and water in substantially equal parts mixed together in the presence of sufficient heat to cause a ready dissolving of the glue in the water, the glycerin serving the function of

keeping the resulting product permanently soft and pliable; in other words, preventing its drying out and cracking.

Having thus described my invention, what 5 I claim as new and desire to secure by Letters Patent, is:—

A hose for carrying gasolene consisting of a flexible metallic supporting frame, a layer of protecting material unaffected by the 10 metal of the frame and insoluble in gasolene, a layer of gelatin material over the protecting layer, entirely excluded from contact with the frame by said protecting layer,

and a second protecting layer of woven water-proof material applied over said gelatin layer and without treatment subsequent to the application thereof over the gelatin layer. 15

In witness whereof, I have hereunto subscribed my name in the presence of two witnesses. 20

JAMES FENTRESS.
